UNITED STATES PATENT OFFICE.

EZRA B. SMITH, OF CHICAGO, ILLINOIS, ASSIGNOR TO THE KINNEAR MANUFACTURING COMPANY, OF COLUMBUS, OHIO, A CORPORATION OF WEST VIRGINIA.

FIRE-CURTAIN.

1,207,806.

Specification of Letters Patent. Patented Dec. 12, 1916.

Application filed December 1, 1911. Serial No. 663,190.

To all whom it may concern:

Be it known that I, EZRA B. SMITH, a citizen of the United States, residing at Chicago, county of Cook, State of Illinois, have 5 invented a certain new and useful Improvement in Fire-Curtains, and declare the following to be a full, clear, and exact description of the same, such as will enable others skilled in the art to which it pertains to make 10 and use the same, reference being had to the accompanying drawings, which form a part of this specification.

My invention has for its object to produce a novel and simple mechanism for controlling a fire curtain in such a manner that it 15 may be raised and lowered at will, be dropped instantly in case of fire and be capable of being raised easily after an emergency release.

20 A further object of my invention is to provide a fire curtain or the like with a service spring which normally holds it raised and a device for checking the drop of the curtain in an emergency, together with 25 means for rendering the service spring inoperative in an emergency without releasing the tension of the spring and at the same time throwing into action the device for checking the falling curtain.

30 A further object of my invention is to provide means whereby a fire curtain or the like may be fully raised by means of its counter-balancing device, even after an emergency release of the curtain.

35 A further object of my invention is to provide means whereby the tension of the service spring may be increased at will by manipulating the curtain.

40 A further object of my invention is to provide means whereby a fire curtain may be given an emergency operation for testing purposes, without interfering with the fusible connections which normally control the emergency operations.

45 A further object of my invention is to provide a fire curtain or the like with a service spring which is rendered inoperative as a counter-balance at the beginning of an emergency operation of the curtain without 50 having its tension released and which is again operatively connected to the curtain after the latter has dropped so as to exert its tension in the direction to lift the curtain.

55 A further object of my invention is to provide a simple, novel and effective baffle plate

for preventing a fire from passing around over the curtain from one side to the other.

A further object of my invention is to provide a simple and novel means for attaching the guides for the edges of a fire curtain so that the guides are permitted to expand under intense heat and therefore be protected against warping or buckling.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front view of a wall having an opening therein closed by a curtain arranged in accordance with a preferred form of my invention; Fig. 2 is a section on line 2—2 of Fig. 1, the scale being somewhat larger than in Fig. 1; Figs. 3 and 4 are details of the fastening means for the channels or guides for the edges of the curtain; Fig. 5 is a longitudinal section on an enlarged scale through the curtain roller and its housing; Fig. 6 is a section on an enlarged scale of the left hand end of the curtain roller as viewed in Fig. 5; Fig. 7 is a section on line 7—7 of Fig. 5, looking in the direction of the arrows; Fig. 8 is a section on line 8—8 of Fig. 5; Fig. 9 is a section on line 9—9 of Fig. 5; Fig. 10 is a transverse section through the housing for the curtain; Fig. 11 is an end view looking toward the left in Fig. 5; Fig. 12 is a detail of the barrel shaft with its automatic locking nut; Figs. 13 and 14 are details showing the construction of the curtain; and Fig. 15 is a detail of a second form of checking device for the curtain.

In Figs. 1 to 14 I have illustrated an arrangement in which all of the various features which can be combined in one form of my invention have been so combined and I shall explain, as the description develops, how certain of the features may be omitted or used in other combinations with each other.

Referring to the drawings, 1 represents a curtain roller or barrel upon which may be wound a curtain of any usual or suitable construction. The barrel is surrounded by a housing 2 which also forms the support for the barrel and for the various controlling

devices. In one end of the barrel I have arranged a shaft 3 which is revolubly supported by the barrel. One end of the shaft projects beyond the barrel and passes through the end wall 4 of the housing, as indicated at 5. The barrel contains within its end a block 6 within which the shaft bears. The block 6 in turn has a bearing upon a member 7 carried by a transverse partition wall 8 in the housing. Consequently one end of the barrel is revolubly supported upon a bearing carried by the housing and also upon the shaft. Surrounding the shaft within the barrel is a spring 9 which has its inner end fixed to the shaft as indicated at 10 and has its outer end fixed to the block 6. Consequently when the shaft is held stationary and the barrel rotated, the spring is wound or unwound depending upon the direction of rotation of the barrel. If the shaft be left free to rotate, then when the barrel turns, the shaft turns with it and the spring does not come into play except as it serves mechanically to connect the barrel and the shaft. On the extreme outer end of the shaft 3 is a pinion 11 which co-operates with a mutilated gear 12 revolubly mounted adjacent thereto and serving as a locking or holding member. The mutilated gear 12 has a few teeth 13 which are adapted to mesh with the teeth of the pinion 11 in one position of the mutilated gear, this being the locking position. The mutilated gear is held in the locking position by means of a device which will release the gear under an abnormal rise in temperature and thus permit the shaft to rotate its pinion out of engagement with the teeth on the gear. In the arrangement shown, a link 14 is connected at one end to the mutilated gear and at its other end to an arm 15 on a rocker shaft 16 which passes through the housing from one end to the other. The rocker shaft is provided with a comparatively long arm 17 to the free end of which is connected a chain or cable 18 having therein a fusible link 19. The chain or cable passes over suitable pulleys down the wall beside the door opening 20 (see Fig. 1) which the curtain is adapted to cover and is there connected to a suitable controlling lever 21. The member 21 serves to hold the mutilated gear in its locking position, and when it is desired to test the apparatus, the member 21 may be operated to release the mutilated gear without interfering with the fusible link.

It will be seen that when the mutilated gear is released, the barrel shaft is left free so that it can turn with the curtain; therefore in case of fire which causes the fusible link to melt, the curtain is freed from the tension of the service spring and can drop under its own weight. However, as soon as the end of the barrel shaft is released the spring tends to unwind until it is no longer under tension. It is one of the purposes of my invention to prevent this unwinding of the service spring because I desire to utilize its initial tension for the purpose of raising or assisting to raise the curtain after an emergency drop has been made; this being either for the purpose of permitting the curtain to be lifted partially to enable a person who has been trapped by the curtain to escape, or for the purpose of permitting the curtain to be restored to its normal condition after the fire is over or the danger past. I therefore provide means for locking the spring upon itself as soon as the barrel shaft is released, thus retaining the tension in the spring even after it has been made inoperative as a counterbalance for the curtain. I accomplish this by the following means: On the portion of the shaft extending beyond the barrel I arrange a coarse screw 23 (see Figs. 5 and 12) and on this screw I place a comparatively heavy nut 24 which is free to move back and forth along the shaft under the control of the threads on the shaft. The outer end of the block 6 is provided with a series of ratchet teeth 25 and the side of the nut which faces the block is provided with a complementary set of teeth 26. When the barrel shaft is released, the service spring being under tension, the shaft is given a quick turn by the spring as the latter begins to unwind. The inertia of the nut 24 makes it slow to follow the turning movement of the shaft and therefore the shaft rotates within the nut and screws the nut inward toward the end of the barrel, a turn or a partial turn of the shaft serving to move the nut against the end of the block 6 in the barrel and bring the ratchet teeth 25 and 26 into engagement with each other. The nut is thus locked to the barrel and can only rotate as the barrel rotates. Consequently further independent rotation of the barrel shaft is prevented because the shaft cannot turn independently of the nut without moving the nut along the shaft, such movement of the nut being prevented because the nut has already been brought against the end of the block which forms part of the barrel. It will therefore be seen that when the barrel shaft is unlocked or released either by reason of a fire or by reason of the manual manipulation of the controlling lever 21, the curtain is freed from the restraining influence of the service spring and immediately begins to drop under its own weight. The tension of the service spring is not lost, however, but is conserved for future use.

Some means must be provided for checking the descent of the curtain since otherwise, particularly in the case of a heavy curtain, it might fall with such force as to break itself loose, break apart, or injure the structure upon which it is mounted. I

have therefore provided an auxiliary counterbalance or checking device which is normally out of action and is brought into play only when the service spring is disconnected and the curtain begins to drop. The auxiliary checking device may take various forms. In Figs. 5 and 6 I have illustrated a hydraulic check, while in Fig. 15 I have shown a second spring which serves to ease the descent of the curtain. Referring first to the arrangement shown in Figs. 5 and 6, 27 represents a shaft revolvably supported at the center of the barrel in the end opposite to that in which the service spring is located. 10 The outer end of the shaft 27 projects beyond the end of the barrel and through a transverse partition wall 28. The wall 28 is provided with a suitable bearing member 29 through which the shaft extends and 15 upon which a block or head 30 in the end of the curtain barrel is revolvably supported. On the outer end of the shaft 27 is secured a pinion 31 which may be engaged by any suitable device for locking the shaft against 20 rotation. In the arrangement shown, (see Fig. 9) there is a lever 32 pivotally mounted on the wall 28 adjacent to the pinion 31 and provided with a tooth block which is adapted to be moved into and out of engagement 25 with the pinion 31. A spring 34 tends normally to swing the lever so as to carry the block into engagement with the pinion and thus lock the shaft 27 against rotation. The adjacent end of the shaft 16, which controls 30 the mutilated gear at the opposite end of the device and extends entirely across the housing, is provided with an arm 35 which is connected by means of a link 36 to the free end of the lever 32. The parts are so proportioned that when the shaft 16 is in the angular position which causes the shaft 3 to be locked it holds the lever 32 down so as to leave the pinion 31 free. Consequently during the normal operation of the curtain, that 35 is when it is raised and lowered, except in emergencies, the shaft 27 is free and rotates with the barrel. When the shaft 16 is rotated into the position for unlocking or releasing the pinion on the shaft 3 it carries 40 the lever 32 or permits the spring 34 to carry the lever into the position to lock the pinion 31. Consequently as soon as the curtain barrel is released from the influence of the service spring the shaft 27 is locked against 45 rotation and, as the curtain drops and rotates the barrel, the barrel moves relatively to the shaft 27. I make use of this condition in the following way: The space between the bearing head 40 for the inner end 50 of the shaft 27 and the head 30 at the end of the barrel serves as a liquid containing chamber. The shaft 27 is provided with screw threads 41 extending throughout that portion lying between the heads 30 and 40 55 and meshing with these screw threads is a piston-like nut 42 which fits in the barrel and is splined thereto so that it must rotate with the barrel while free to move lengthwise thereof; 43 representing a spline or key extending lengthwise on the inside of the 60 barrel and engaging with the piston nut. The piston nut is provided with openings 44 extending therethrough in the direction of the length of the barrel. On the inner side of the nut these openings may be closed 65 by simple flap or check valves 45. Therefore the nut may travel in one direction without encountering any considerable resistance because the air or other fluid may pass freely through the openings 44 unchecked by the 70 valves. When the piston moves in the opposite direction the pressure against the valves holds them closed and the air or other fluid in advance of the piston will be compressed unless some other outlet is provided for it. 75 In the arrangement shown I have made the shaft 27 hollow and have provided it with one or more openings 46 leading from the outer surface to the interior at points near the ends thereof. The hollow shaft with its 80 ports or outlets at the ends serves as a conduit through which the liquid from one side of the piston may flow to the other side as the piston advances from the end toward the middle of the barrel. The screw threads are 85 so disposed that when the shaft 27 is locked and the barrel is turned by a descending curtain, the piston moves in the direction to close the valves 45 and, with the air or other fluid lying between the piston and the head 90 40, it forms an air or hydraulic check which eases the descent of the curtain. The resistance offered by the checking device depends upon the size of the ports 46 and also upon the nature of the checking fluid. This fluid 95 may consist simply of the air contained within the barrel or, in the case of heavy curtains, the chamber between the heads 30 and 40 may be wholly or partially filled with an oil having a high flashing point. When 100 air alone is used the resistance of the checking valve is comparatively small. If the chamber is entirely filled with an oil or other liquid the resistance will be comparatively great and will be imposed as soon as the 105 shaft 27 is locked. If the chamber is only partially filled with a liquid then the curtain will be permitted to drop through any desired distance before it encounters much 110 more resistance than results from the compression of the air because the liquid has an opportunity to bank up ahead of the piston before its volume begins to decrease by reason of its being discharged through the 115 hollow pipe.

In Fig. 15 I have shown a modified form of checking device in the form of an auxiliary spring which is wound up as the curtain drops during an emergency operation and stores power which is afterward avail- 120

able for the purpose of lifting the curtain. In this arrangement the shaft 27^a, corresponding to the shaft 27 has fastened to it one end of a coiled spring 48, the other end 5 of which is attached to the head 30^a in the end of the curtain barrel. In this form of my invention, the auxiliary spring offers no resistance to the turning of the curtain barrel as long as the shaft 27^a is unlocked, because the shaft can rotate with the barrel. As soon, however, as the shaft 27^a is locked and the curtain begins to descend, the auxiliary spring 48 is wound up, its tension increasing as the curtain descends. It will thus be seen that I have provided the curtain with a service spring which becomes inoperative in an emergency without, however, losing its tension, so that the curtain is free to drop under its own weight as soon as the emergency occurs. It will also be seen that I have provided means which, while not interfering with the descent of the curtain, yet checks it gradually so as to prevent it from falling with a wrecking force. Furthermore, in one form of the checking device, that employing the auxiliary spring, I not only regulate the descent of the curtain but I store up energy which may afterward be used to aid in again raising the curtain.

Where the checking device is in the form of the auxiliary spring which stores up power as the curtain descends during an emergency operation, the curtain may readily be lifted a short distance to permit the passage of a person who may have been trapped by the curtain or for other purposes. The power stored in the auxiliary spring is also sufficient to permit the curtain to be lifted readily and rolled up to the top of the opening which it is adapted to close, the service spring remaining out of operation during this time. When the curtain is almost completely rolled up the mutilated gear 12 may be brought into locking position by pulling on the chain 18, the fusible link 19 having in the meantime been replaced. Then during the last portion of the upward movement of the curtain the barrel rotates the shaft 3 so as to bring the mutilated gear into the position indicated in Fig. 8 and the shaft and barrel come to rest. This operation has released the auxiliary spring so that it no longer exerts any influence upon the curtain. The curtain may now be drawn down by hand and, in so doing, the barrel rotates relative to the shaft 3 and backs the nut away out of its locking position, throwing the entire tension of the service spring upon the barrel and making the service spring serve again as a counterbalance for the curtain; the parts, including the tension of the service spring being in the same condition as they were before the emergency operation, there having been no unwinding of the serv-

ice spring and consequently the service spring requiring no rewinding after the curtain has been raised. The operation is just the same as that described when the curtain is given an emergency release for testing purposes by operating the controlling lever 21.

The arrangement employing the auxiliary spring and operating in the manner just described is applicable to curtains which are not excessively heavy. For heavy curtains I prefer to use the fluid check instead of the auxiliary spring. In this case some means must be provided for again connecting the service spring in such a way as to permit its tension to be exerted in the direction to raise the curtain after an emergency operation. This may be done either automatically or by manually controlled means. The simplest arrangement is that which is manually controlled, it being simply necessary to place upon the end of the spring shaft 3 some means by which the shaft may be manually rotated. In the arrangement shown, see Figs. 5 and 11, there is placed on the shaft 3 a loose gear 50 which meshes with a pinion 51 mounted on the housing adjacent thereto. The pinion may be rotated in any suitable way, as by means of a sprocket chain 52 passing over a sprocket wheel 53 which is connected to the pinion. Fixed to the shaft 3 adjacent to the gear 50 is a ratchet wheel 54 with which a pawl or dog 55 carried by the gear is adapted to cooperate.

The pawl and ratchet wheel are so disposed that when they are in engagement with each other the gear wheel and therefore the shaft 3 can only be driven by the pinion in the direction to wind up the service spring, a rotation of the gear wheel in the opposite direction permitting the pawl to slip over the ratchet wheel without producing any turning movement on the shaft. It is desirable that the sprocket chain hang idle and have no movement during the ordinary operations of the curtain and therefore I prefer to construct the pawl so that it will normally be out of engagement with the ratchet wheel, this being accomplished either by counter-weighting the pawl or providing it with a spring. Therefore the shaft may ordinarily rotate in either direction without moving the sprocket chain. When it is desired to turn the spring shaft manually, the pawl may be brought into engagement with the ratchet by drawing upon a rod or chain 56 which is attached at one end to the pawl and extends down to a point within easy reach of an operator. By this arrangement, after the curtain has made an emergency operation, the nut 24 being locked to the barrel, the spring shaft may be turned by pulling on the sprocket chain and thus back the nut away from the spring barrel 125 130

- and impose the tension of the spring on the barrel. The tension in the spring is now only that which it had before the curtain began to descend and is not as great as it would have been had the curtain been drawn down against the tension of the spring. The extra tension may be placed in the spring by pulling upon the sprocket chain and rotating the spring shaft through a sufficient number of turns. If desired an excess of tension may be placed in the spring, by a continued pull on the sprocket chain, so that the spring will raise the curtain of its own accord and without the assistance which it is intended that a curtain shall ordinarily have. Whenever the spring has been re-wound to the desired extent, the spring shaft may be locked by means of the mutilated gear as heretofore explained.
- It may sometimes be desirable to have the spring unlocked from the barrel automatically when the curtain nears the bottom of its descent during an emergency operation, so that the curtain is ready to be lifted when it is clear down without first rewinding the spring or performing any other manual operation except that of lifting on the curtain. To this end I have provided the arrangement best shown in Figs. 5, 7 and 8. Referring to these figures, 60 represents a gear wheel fixed to the barrel, preferably by mounting it upon the end of the block 6. This gear wheel meshes with a gear wheel 61 loosely mounted upon a shaft 62 which is revolvably supported in the walls 4 and 8 of the housing with its axis parallel to the axis of the barrel. Fixed to the shaft 62 is a ratchet wheel 63 and on the gear wheel 61 is a pawl or dog 64 which is adapted to cooperate with the ratchet wheel. It is intended that the pawl be normally out of engagement with the ratchet wheel and I have therefore provided it with a spring 65 which holds it away from the ratchet wheel. The shaft 62 carries a pinion 66 meshing with an idle pinion 67 which in turn meshes with the pinion or gear 11 on the spring shaft. When the pawl is in engagement with the ratchet wheel, a rotation of the barrel in the direction produced by a falling curtain causes the pawl to drive the ratchet wheel and therefore, through the intermediate gearing, the spring shaft is also driven; the direction of rotation of the spring shaft being against the resistance of the spring. It will thus be seen that when the gearing which I have just explained is thrown into operation the spring shaft is turned in just the opposite direction from that in which it moves when released for an emergency application. Therefore when this gearing is thrown into action after an emergency operation, the nut having been screwed into engagement with the barrel, a relative turning movement between the nut and the shaft takes place in the direction to back the nut away from the barrel and unlock the working end of the spring from the barrel. As soon as this occurs, the spring is in a position to exert its tension in the direction to lift the curtain, the power of the spring being transmitted through the train of gearing.
- The pawl 64 may be thrown into engagement with the ratchet wheel at the proper point in the descent of the curtain in any suitable manner. In the arrangement shown there is a cam lever 70 mounted upon one of the end walls of the housing in the plane of the pawl 64. Normally the cam lever is out of the path of the pawl as the pawl rotates with its gear, but means are provided for swinging one end of the lever into the path of the pawl so that as the pawl reaches it during its rotation it is pressed inwardly into engagement with the ratchet wheel and is held there as long as the gearing is under strain. The cam lever is connected in a suitable manner so that it will be thrown into action by the curtain just before the curtain reaches the bottom of its descent. In the arrangement shown, one end of the cam lever has attached thereto a rod 71 provided with a hooked portion 72 the end 73 of which is adapted to be caught by a pin on one edge of the curtain and be drawn down, thus rotating the lever into position to engage with the pawl. Normally the member 73 is held out of the path of the pin on the curtain by means of an arm 74 on the controlling shaft 16, this arm engaging the hook and holding it in inoperative position as long as the shaft 16 occupies the position wherein it locks the spring shaft 3, that is the member 73 is held out of the path of the pin on the curtain as long as the shaft 16 is not in an emergency position. As soon as the shaft 16 assumes an emergency position the arm 74 is withdrawn from the hook, and the latter, being made of spring metal, jumps back so as to carry the end 73 into the path of the pin on the curtain. I have illustrated the pin on the curtain at 75 in Fig. 2. In order that the cam lever may be operated manually I have provided it with a rod 76 which extends down beside the opening which is adapted to be closed by the curtain to a point within easy reach of a person standing adjacent to the opening.
- The operation of the mechanism just described is as follows: Assuming that the curtain has been released for an emergency operation, the locking nut having been shifted over into engagement with the barrel, and the curtain having begun its descent under the control of the checking device—the curtain descends until the pin 75 engages with the end 73 of the hook, the hook being drawn down with the curtain 120
- 125
- 130

and swinging the cam lever into the path of the pawl 64. The pawl is constantly rotating with the gear wheel on which it is mounted and therefore it strikes the raised cam lever and is brought into engagement with the ratchet wheel so that the spring shaft becomes geared to the barrel. As I have heretofore explained, the rotation of the shaft which now ensues is in the direction to back the locking nut away from the curtain barrel so that the power of the spring again comes upon the barrel. This occurs just before the curtain comes to rest so that when the curtain is completely down the spring serves as a partial counterbalance which permits the curtain to be raised easily, the spring exerting its tension through the train of gearing. The service spring of course only has its initial tension which is less than the tension which it would have under ordinary conditions where the curtain is simply drawn down against the tension of the spring and, for the purpose of increasing the tension of the spring to any desired extent I prefer so to proportion the gearing between the barrel and the shaft that when the curtain is drawn down with the gearing in action it places in the spring a tension in excess of that which would occur under ordinary conditions with the shaft locked. Therefore, after the curtain has been partially or wholly raised, it may be drawn down so as to wind up the spring and then the shaft may be locked by means of the mutilated gear in the manner heretofore explained, and the curtain be raised again; the spring being unwound a less number of turns during the lifting of the curtain than it was wound by the descending curtain. As soon as the shaft 3 is locked and the curtain begins to rise, the pawl 64 automatically disengages itself from its ratchet wheel. In this manner the spring may be wound up so as to give it any desired tension by simply raising and lowering the curtain, unlocking the shaft during the lowering of the curtain and throwing in the winding gearing upon the lowering of the curtain and locking the shaft when the curtain is raised.

The rod 71 may have a flexible portion as indicated at 77 so that the hook may be carried down a short distance after the cam lever has been brought into working position, thus insuring that the lever will be brought into the working position without requiring that the adjustment of the parts be extremely accurate.

The curtain may take any usual or desired form, but I prefer to make it of a series of corrugated sections 80 which are suitably interlocked with each other, each section having several corrugations so as to give great strength without making the curtain

too thick or giving it too great weight. The sections may be held together by means of short plates 81 arranged on opposite sides thereof and having fingers 82 which lie in the corrugations where they are secured. These plates are preferably as wide as the thickness of the curtain so that they may act as shoes to fill the channels in which the edges of the curtain run, taking the wear resulting from the frictional contact between the curtain and the guides, holding the curtain in alinement, and preventing fire from passing around the edges of the curtain.

It is necessary to provide some means for preventing the fire from passing from one side of the curtain through the housing and around to the other side of the curtain and for this purpose I have provided a novel form of baffle plate which comes into action not only in an emergency but whenever the curtain is drawn down to its full extent, thereby preventing the bearings from becoming rusty and insuring that the baffle plate will operate when it is needed. Furthermore, by having the baffle plate controlled directly from the curtain, it will always be in position when the curtain is down so that it does not depend upon a dangerous rise in temperature to place it in working position and therefore with the curtain affords a perfect fire proof covering which may be placed in position across an opening before a fire reaches it. The housing has an inwardly extending flange 83 lying below the curtain barrel and adjacent to this flange is pivotally mounted a baffle plate or cover 84, extending throughout the length of the housing and preferably pivoted so as to move about a longitudinal axis at about the center of the plate. The plate is so proportioned that one edge underlies the flange 83 and when it is swung about so as to bring this edge into engagement with the flange the opposite edge presses against the curtain and makes a tight joint. I prefer to curl the edge of the plate which engages with the curtain as indicated at 85 so that the plate may be drawn against the curtain with a yielding pressure. The plate is preferably counter-weighted so that it will automatically swing away from the curtain when free to do so and it is provided with an arm 86 which is adapted to be engaged by a pin 87 on the curtain just before the curtain descends far enough to completely close the opening which it is adapted to cover. Therefore as the curtain completes its descent the pin carries the arm down and swings the baffle plate into its working position.

The edges of the curtain ride in suitable channels 90 and 91, these being attached to the wall 92 at the sides of the opening which the curtain is to cover. In case of a severe fire which will heat the fire door and the

channels or guides to a high temperature, there will be an unequal expansion between the material of the wall and the material of the guides and therefore, unless some means is provided to compensate for this difference in expansion, the guides will buckle and warp and allow openings to form around the curtain. I have provided a novel means for attaching the guides which will support them firmly under normal conditions and yet will permit them to expand and contract naturally under great temperature changes. To this end I have provided the guides with elongated openings 93 through 15 which pass the bolts 94 which attach the guides to the wall. The openings are preferably made not only elongated but larger in every direction than the diameter of the bolts, so as to permit freedom of relative 20 movements between the guides and the bolts in any direction. Between the nuts 95 on the bolts and the guides I place split helical spring washers 96 which will not be quite closed when the guides are originally secured in place. In case of a fire, the washers will become hot and will lose their temper so that they no longer have a secure grip on the guides and the guides may therefore 25 expand freely. If desired, the usual heavy 30 plate 97 on the bottom of the curtain may be fastened to the curtain proper by the same kind of fastenings as those employed for securing the guides to the wall, such fastenings being indicated at 98. By this arrangement the unequal expansion which may 35 take place between the thinner corrugated sections and the heavy plate will not produce a buckling of the curtain.

It will thus be seen that I have produced 40 a number of novel features which may be combined in various ways to produce an effective fire curtain which operates and which may be controlled in any desired manner: taking care of the demand for the simplest arrangement in which the curtain is 45 simply dropped without releasing the tension of its service spring; of an arrangement in which there is means for simply winding the service spring, (the sprocket and chain); of an arrangement in which the curtain may 50 be released for test purposes without disturbing the fusible connections; of an arrangement in which the easing of the descent of the curtain during an emergency 55 operation and the subsequent raising thereof is accomplished by an auxiliary spring; and of arrangements which employ very heavy curtains and therefore require a powerful checking device.

60 I claim:

1. In combination, a barrel, means for 65 revolvably supporting said barrel, a curtain on said barrel, a counter-balancing spring lying within said barrel and secured at one end thereto, a shaft connected to the other

end of the spring and revolvably supported by the barrel, means for normally holding said shaft against rotation, and means actuated by the rotation of the shaft for locking the ends of the spring against relative movement. 70

2. In combination, a curtain, a service spring for counter-balancing the curtain, mechanism for rendering the spring inoperative as a counter-balance without releasing 75 its tension, restraining means for said mechanism adapted to be rendered inoperative upon a predetermined rise in temperature, said mechanism including a part controlled by the curtain for restoring the spring to 80 operativeness.

3. In combination, a curtain, a service spring normally under tension for counter-balancing the curtain, mechanism actuating 85 upon a predetermined rise in temperature for rendering the spring inoperative as a counter-balance and at the same time locking it against unwinding, and means for automatically restoring the spring to operativeness as a counter-balance after the curtain has descended a predetermined distance 90 below the point it occupied when the spring was locked.

4. In combination, a curtain, a barrel for the curtain, a service spring connected at 95 one end to the barrel, a holding device for the other end of the spring, means acting upon a predetermined rise in temperature for detaching the latter end of the spring from said device and locking it against 100 movement relative to the other end, and means controlled by the curtain for returning the spring to service condition.

5. In combination, a curtain, a counter-balancing spring connected at one end to 105 said curtain, a revolvble screw-threaded shaft connected to the other end of the spring, a nut having considerable inertia loosely mounted on said shaft, means co-operating with said nut in one position of the nut to lock the ends of the spring against 110 relative movement, and means including a fusible element for normally holding said shaft against rotation.

6. In combination, a fire curtain, a barrel for the curtain, a spring connected at one end to the barrel, a holding device for the other end of the spring, means for disconnecting the latter end of the spring from 115 the said device and locking it to the barrel, and means controlled by the curtain for 120 unlocking the last-mentioned end of the spring from the barrel.

7. In combination, a curtain, a service spring for counterbalancing the curtain, a 125 device for checking the descent of the curtain, and automatic means for rendering the spring inoperative as a counterbalance without releasing its tension and simultaneously connecting said device to the curtain. 130

8. In combination, a curtain, a service spring for counterbalancing the curtain, a device for checking the descent of the curtain, means for rendering the spring inoperative as a counterbalance without releasing its tension and simultaneously connecting said device to the curtain, and means for again rendering the spring operative as a counterbalance while retaining its tension.
10. 9. In combination, a curtain, a service spring for counterbalancing the curtain, a device for checking the descent of the curtain normally disconnected from the curtain, and mechanism controlled by the spring for locking its ends against relative movement and simultaneously connecting said device to the curtain.
10. In combination, a fire curtain, a service counterbalance for the curtain, means including a fusible element for rendering said counter-balance inoperative to resist the descent of the curtain, a member including a flexible connection extending from said means, and a combined locking and operating device secured to the free end of said connection.
11. In combination, a curtain, a service spring for counterbalancing the curtain, and means including a train of gearing adapted to be connected between the curtain and the spring for increasing the effective tension of the spring upon drawing the curtain in one direction and then returning it to the starting point.
12. In combination, a curtain, a revoluble support for the curtain, a counterbalancing spring connected at one end to said support, a screw-threaded member connected to the other end of the spring, a movable nut on said screw-threaded member for locking the ends of said spring against relative movement, and a holding device for said member.
13. In combination, a curtain, a revoluble support for the curtain, a counterbalancing spring connected at one end to said support, a screw-threaded member connected to the other end of the spring, a movable nut on said screw-threaded member for locking the ends of said spring against relative movement, a holding device for said member, and means actuated upon a predetermined rise in temperature for releasing said member from said holding device.
14. In combination, a curtain, a revoluble support for said curtain, a counterbalancing spring connected at one end to said curtain, a revoluble screw-threaded shaft connected to the other end of said spring, a nut having considerable inertia mounted on said shaft and movable from a position in engagement with said revoluble support to an inoperative position, and means including a fusible member for holding said shaft.
15. In combination, a barrel, means for revolubly supporting said barrel, a curtain on said barrel, a service spring lying within the barrel and connected at one end thereto, a revoluble member connected to the other end of said spring and projecting beyond the end of said barrel, means including a fusible member for holding the projecting end of said revoluble member, and means actuated by said member upon the rotation thereof to lock said member to the barrel.
16. In combination, a barrel, means for revolubly supporting said barrel, a curtain on said barrel, a counterbalancing spring lying within said barrel and secured at one end thereto, a shaft connected to the other end of the spring and revolubly supported by said barrel, means including a fusible element for normally holding said shaft against rotation, and means actuated by the rotation of said shaft for locking it to the barrel.
17. In combination, a curtain, a service spring for counter-balancing the curtain, a screw-threaded member controlled by the spring, and means associated with said screw-threaded member for locking the ends of the spring against relative movements.
18. In combination, a revoluble curtain support, a curtain on said support, a counterbalance for said curtain, a member movable longitudinally of said support for locking said counterbalance in an inoperative condition, and means controlled by the counterbalance for actuating said member.
19. In combination, a curtain, a service spring for counterbalancing the curtain, means including a screw-threaded member controlled by the spring for locking the ends of the spring against relative movement, and a restraining device for said member adapted to be rendered inoperative upon a predetermined rise in temperature.
20. In combination, a curtain, a revoluble support for the curtain, a counter-balancing spring connected at one end to said support, a screw-threaded member connected to the other end of the spring and adapted to be rotated thereby, a holding device for said member, means actuated upon a predetermined rise in temperature for releasing said member from said holding device, and a loose nut on said member having considerable inertia so as to compel it to move axially of said member upon a sudden rotation of the member to lock the ends of said spring against relative movement.
21. In combination, a curtain, a counterbalance for said curtain, a fluid pressure check device normally disconnected from the curtain, and means for rendering the counter-balance inoperative and at the same time connecting the check device to the curtain.
22. In combination, a curtain, a counterbalance for the curtain, means for rendering the counter-balance inoperative to resist the

descent of the curtain, a holding device for said means, a normally inoperative fluid pressure check device for retarding the descent of the curtain, and means acting upon a predetermined rise in temperature for releasing said holding device and simultaneously rendering the check device operative.

23. In combination, a curtain barrel, a curtain on said barrel, a counter-balancing spring in one end of the barrel, a normally inoperative fluid pressure check device in the opposite end of the barrel, means for rendering said spring inoperative to retard the descent of the curtain, a restraining device for said means, and means actuated upon a predetermined rise in temperature for releasing said restraining device and at

the same time rendering said check device operative.

24. In combination with a fire shutter, a shutter carrying member, a counter-balance means permanently maintained in operative condition, a retarding means, said counter-balance means being normally connected to said member, and means for disconnecting said counter-balance means from said member and connecting said retarding means.

25. In testimony whereof, I sign this specification in the presence of two witnesses.

EZRA B. SMITH.
